FIGURINE

Richard E. Thompson, San Diego, Calif., assignor to The San Diego Hockey Club, San Diego, Calif., a corporation of California

Filed Sept. 23, 1968, Ser. No. 13,685

Term of patent 14 years

Int. Cl. D11—02, 99

U.S. Cl. D29—23

FIG. 1 is a front perspective view of a figurine showing my new design;

FIG. 2 is a side elevational view thereof;

FIG. 3 is a side elevational view of the side opposite thereto with the head portion in cross section; and

FIG. 4 is a back elevational view.

I claim:

The ornamental design for a figurine, substantially as shown.
